UNITED STATES PATENT OFFICE.

ROE TANNER, OF ATTICA, OHIO.

PROPELLER.

1,195,624.

Specification of Letters Patent. Patented Aug. 22, 1916.

Application filed March 13, 1915. Serial No. 14,282.

To all whom it may concern:

Be it known that I, ROE TANNER, a citizen of the United States, residing at Attica, in the county of Seneca and State of Ohio, have invented a new and useful Propeller, of which the following is a specification.

This invention relates to propellers of that type especially designed for use in connection with dirigible balloons, aeroplanes and 10 the like, one of the objects of the invention being to provide a propeller having adjusting mechanism whereby the pitch of the blades can be varied at will without interfering with the rotation of the propeller, thus 15 to increase or reduce the effectiveness of the propeller as a driving medium.

Another object is to provide improved means for mounting the propeller whereby it may be held against vibration while 20 rotating at a high speed.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a vertical longitudinal section through a structure embodying the present improvements. Fig. 2 is a front elevation of the propeller.

Referring to the figures by characters of reference 1 designates portions of the air ship to which the present improvements are 40 applied, said portions being provided with bearing rings 2 having interior raceways 3 carrying anti-friction balls 4 engaged by rings 5 mounted for rotation in the rings 2. The rings 5 are connected by any suitable 45 means, such as strips 6 whereby they will rotate together. Furthermore these rings 5 are connected by spiders 7 to hubs 8 which are secured in any suitable manner to the drive shaft 9 of the propeller. One of the 50 hubs 8 has a flange 10 to which is secured the hub 11 of the propeller, this hub being connected by spokes 12 to a circular rim 13.

The spokes may be formed of wire somewhat after the manner of the spokes of ordinary 55 bicycle wheels, although spaced apart greater distances. Thus the rim 13 is held

concentric with the hub 11 and will rotate therewith. Interposed between hub 11 and rim 13 are segmental blades 14, each blade having bearing studs 15 extending from the outer and inner ends thereof, the outer studs 15 being mounted within the rim 13 while the inner studs bear within the hub 11. Said inner studs 15 have radial arms 16 to which are pivotally connected actuating rods 17. These rods extend through the spiders 7 and are connected to a flange 18 at one end of a sleeve 19 which is feathered on the shaft 9. Said sleeve has an annular groove 20 within which is arranged a ring 21, this ring being pivotally engaged by the forked end 22 of a lever 23. This lever is fulcrumed as at 24 upon the air ship structure and has oppositely extending arms 25 connected by cables 26 or the like to opposed 75 arms of a lever 27. This lever is mounted where it can be easily manipulated by the aviator and any suitable means may be provided for locking the lever in any position to which it may be adjusted. This means is 80 preferably in the form of a toothed segment 28 and a pawl 29. Suitably arranged guide wheels 30 are mounted on the air ship for engaging the cables 26 to hold them in proper positions.

It will be apparent that when the shaft 9 is driven in the usual manner the hub 11 and rim 13 will be rotated therewith, carrying the blades 14. Likewise the rings 5 will rotate together within the rings 2 and will 90 operate to prevent the shaft 9 and the propeller from vibrating during the rotation thereof at a high speed. At any time during such rotation, the sleeve 19 may be shifted longitudinally so that motion will 95 be transmitted through the rods 17 to the crank arms 16, thus swinging the blades 14 simultaneously about their axes of rotation, thereby to adjust them angularly, thus to increase or diminish their effectiveness as propelling mediums. It will be noted that the rings 5 project into channels in the inner faces of the rings 2 so that the shaft 9 and the parts carried thereby are thus held 100 against longitudinal displacement.

What I claim is:—

The combination with a structure having spaced bearing rings, and connected rings revolvable within said bearing rings, of a solid drive shaft extending through the centers of said connected rings and revolvable therewith, a propeller revolvable with said

shaft and the connected rings and including radial blades movable about individual radial axes, a sleeve revoluble with and slideable upon the shaft, actuating rods fixedly connected to the sleeve and extending through the connected rings, and connections between said rods and the blades.

In testimony that I claim the foregoing as my own, I have hereto affixed my signature in the presence of two witnesses.

ROE TANNER.
